DESIGN FOR A TIE CLASP OR THE LIKE

Michael J. Freiler, Jr., Bridgeport, Conn.

Application April 17, 1948, Serial No. 145,787

Term of patent 7 years

(Cl. D17—10)

To all whom it may concern:

Be it known that I, Michael J. Freiler, Jr., a citizen of the United States, residing at Bridgeport, in the county of Fairfield and State of Connecticut, have invented a new, original, and ornamental Design for a Tie Clasp or the like, of which the following is a specification, reference being had to the accompanying drawing, forming part thereof.

Fig. 1 is a perspective view and Figs. 2, 3, 4 and 5, respectively, are front, plan, front end and rear end elevations of a tie clasp or the like, showing my new design.

I claim:

The ornamental design for a tie clasp or the like, substantially as shown.

MICHAEL J. FREILER, JR.
